UNITED STATES PATENT OFFICE.

REED ADAMS, OF DETROIT, MICHIGAN.

PRINTING PRESS.

Application filed October 17, 1923. Serial No. 669,019.

My invention relates to printing and an object of my improvements is to secure a clean and uniform impress from the type, especially in that class of work in which a part of the type is changed at each operation of the press.

I secure this object in the apparatus illustrated in the accompanying drawing in which:—

10 Figure 1, is side elevation of a printing press embodying my invention. Figure 2 is a detail sectional elevation to an enlarged scale of a part of Figure 1.

Figure 3, is a plan view, partly in section, 15 of a part of Figure 2.

Figure 4 is a detail plan view of the platen and tympan thereon.

Figure 5, is a perspective view showing a provision for changing a part of the type at 20 each operation of the press.

Figure 6, is a detail section on the plane indicated by the line $v-v$ of Figure 5.

a is the frame of the press, carrying the usual conventional parts, by which the chase 25 b' and type b^2 , and the platen with tympan c^4 are carried— b , is the oscillating rocker lock. The platen c is provided with a roller c^2 along its upper edge and with elastic strips c^3 along its lower edge.

30 d is a shaft extending from side to side of the frame, d^2 is a roller thereon and d^3 is a pawl adapted to rock about said shaft.

e is a second shaft bearing in the frame a and extending parallel to the shaft d . e^3 is a 35 roller on the shaft e and e^2 is a ratchet wheel on said shaft secured to said roller.

The pawl d^3 is adapted to engage the teeth of the ratchet wheel e^2 to turn said wheel and consequently the roller e^3 . bd is a rod 40 connecting the rocker lock b with the pawl d^3 , to oscillate the latter.

f is a shaft, extending parallel to the shafts d and e and having a roller f^2 thereon. f^3 , (Fig. 3) is a loose pulley on the shaft f , 45 held in frictional engagement with the end of the roller f^2 , by a coil spring f^4 surrounding said shaft.

ef is a belt passing over a pulley or roller on the shaft e and over the pulley f^3 .

50 g , is a shaft resting in the frame a , parallel to the shafts d , e and f ; g^2 is a roller on the shaft g .

p is a roll of paper on the roller g . The paper extends in a strand p^3 from the roll p 55 to and between the elastic strips c^3 , thence over the platen c to and around the roller c^2 ,

thence returning along the surface of the platen and passing between the inner strip c^3 and the edge of the platen, thence partly around the rollers d^2 and e^3 and to the roll p^2 on the receiving roller f^2 .

The operation of the above described apparatus is as follows:

During the operation of the press the oscillation of the rocker lock b actuates the pawl d^3 , which rotates the roller e^3 through the ratchet wheel e^2 , and the rotation of said roller is communicated through the yielding connection above described to the roller f^2 .

The roller e^3 draws the strand p^3 along continually, and the paper after leaving the roller e^3 is wound into the receiving roll p^2 . The strand p^3 is held tight by the frictional action of the strips c^3 so that it lies smooth upon the surface of the platen in two superimposed layers which move a short distance in opposite directions at each operation of the press. The outer layer of the strand p^3 on the platen c , forms the outer surface of the tympan and this surface is changed between consecutive actions of the press, so that the opposing surface opposite the type is renewed after each stroke.

In circular letters where the address at the top of the letter is alone changed after each impression, the impress of the type in the body of the letter and in the address has presented a different appearance, because the surface of the tympan under the type forming the body of the letter was altered by the continual action of the same type thereon.

In the above construction, the impress of the whole type is uniform and remains so.

Circular letters are printed in presses of the usual construction as shown. The body 95 of the letter is on a form that is retained in the press in the usual way until the whole number of letters is printed, while a separate address plate which may also have the salutation thereon, is inserted and removed 100 from the press at each operation. The plates are inserted and removed by hand and the press may be adapted to receive the plate in any well known way. A plate for this purpose is shown in the patent to 105 Joseph Duncan, No. 1,087,223, Feb. 17, 1914, and a particular way of securing an address type in place is shown in the patent granted to me, October 15, 1907, No. 868,315.

Figures 5 and 6 illustrate a form and construction shown in a patent granted to me April 10, 1917, No. 1,221,815, and is shown 110

merely to illustrate the operation of this invention. A represents the type for printing the body of the letter and B the removable plate bearing the address, etc. Said plate is of thin iron and is retained in place by a permanent magnet M. A plate B is removed and replaced by hand at each operation of the press.

What I claim is:

- 10 1. The process of printing circular letters consisting in printing the body of the letter from a permanent form and the address from a type inserted in place at each operation of the press, and providing a new tym-

pan surface at each operation of the press. 15

2. In combination with a printing press having a platen, a tensioning device at one edge of said platen, a roller at the other edge of said platen, a sheet of suitable material passing through said tensioning device, over said platen, and roller and returning over said platen, and means for drawing said sheet of material through said tensioning device and over said platen. 20

In testimony whereof, I sign this specification.

REED ADAMS.
